UNITED STATES PATENT OFFICE.

FRANZ KOSCHTIAL, OF HOBOKEN, NEW JERSEY.

GUIDING ATTACHMENT FOR SEWING-MACHINES.

SPECIFICATION forming part of Letters Patent No. 542,858, dated July 16, 1895.

Application filed November 26, 1894. Serial No. 529,939. (No model.)

To all whom it may concern:

Be it known that I, FRANZ KOSCHTIAL, of Hoboken, Hudson county, New Jersey, have invented an Improved Guiding Attachment 5 for Sewing-Machines, of which the following is a specification.

This invention relates to a guiding attachment for sewing-machines which will properly present the work to the needle, so that 10 the operator need not assist or guide the same by his hands. Thus one operator can oversee a number of machines, which will all work entirely automatically and need only be looked after from time to time, without re- 15 quiring manual assistance.

In the accompanying drawings, Figure 1 is a side elevation of my improved guiding attachment; Fig. 2, a plan thereof; Fig. 3, a rear elevation, partly in section, of the upper 20 spool-carrier; Fig. 4, a rear view of the tension mechanism; Fig. 5, a cross-section on line 5 5, Fig. 4; Fig. 6, a rear view of the guide-bar *d*; Fig. 7, a cross-section on line 7 7, Fig. 6; Fig. 8, a rear view, partly in section, of the 25 folder; Fig. 9, a cross-section on line 9 9, Fig. 8; and Fig. 10, an end view of the plate *f*.

The letter *A* represents the table of a sewing-machine, and *a* is the work-plate. Upon the plate *a* is supported one end of the guide- 30 plate *b*, which is also supported by means of a rail *b'* upon the table *A*. The rail *b'* is slot- 35 ted at its ends, as at *b*², for the reception of clamp-screws *b*³, by which the plate *b* is secured to the rail, so as to be laterally adjust- able. Near its rear end the plate *b* is pro- 40 vided with the tension-bar *c*, beneath which the work *B* passes and by which the work is held down tightly upon the face of the plate.

The tension-bar *c* is attached to the plate *b* 45 by means of the set-screws *c'*, Fig. 4, surrounded by coiled springs *c*², so that the bar is free to yield vertically under pressure. To one face of the bar *c* there is secured by screws *c*³ the clamp-bar *c*⁴, between which and 50 the bar *c* the upwardly-turned ends of a folded flexible strip *c*⁵ are confined, Fig. 5. Within the fold of this strip there is placed a rod *c*⁶, which stiffens the same and causes the lower side of the strip *c*⁵ to bear upon the work *B*, so as to produce the desired amount 55 of frictional tension. After the work has

cleared the tension device *c* it passes under a guide bar or rail *d*, Fig. 6, secured to the plate *b* by the set-screws *d'*, surrounded by the coiled springs *d*². Into the bar *d* there is cut 55 a longitudinal keyway or groove *d*³, which is engaged by the clamp-screws *d*⁴ of a pair of gages *d*⁵. These gages are in this way longitudinally adjustable upon the bar *d*, and they should be set at such a distance apart as to 60 permit the passage of the work between them without lateral deflection. Lugs *d*⁶, depending from the gages *d*⁵ and entering a slot *d*⁷ of plate *b*, prevent the work from slipping 65 with its edges beneath the gages.

In front of the bar *d* there may be placed a folder for upsetting one edge *B'*, Fig. 2, of work *B*. This folder consists of a folding-bar *e*, Fig. 8, longitudinally adjustable on a di- 70 vided grooved rail *e'*, which it engages by a feather *e*². One end of this bar is reduced, as at *e*³, and around this reduced end the fold *B'* is formed by the downwardly-projecting finger *e*⁴ of a hemmer *e*⁵, which is longitudi- 75 nally adjustable upon the rail *e'* by clamp-screw *e*¹⁸. By drawing the bar *e* in or out to any suitable extent and properly setting the hemmer *e*⁵ the location and size of the fold may be readily adjusted.

The rail *e'*, together with the bar *e*, is 80 pressed down at one end upon the work by a presser-plate *e*⁶, free to move vertically upon the pins *e*⁷, surrounded by the coiled springs *e*⁸. These pins carry above the presser-plate *e*⁶ a fixed plate *e*⁹, through which projects the 85 clamp-screw *e*¹⁰. The other end of rail *e'* may be pressed down by set-screw *e*¹¹, surrounded by coiled spring *e*¹². By setting the screws *e*¹⁰ *e*¹¹ the pressure of the bar *e* upon the work *B* may be regulated. Of course when the 90 folder is used the gages *d*⁵ and hemmer *e*⁵, together with rod *e*, are so set that the fold *B'* is fed to the needle.

Before the work reaches the needle it is 95 guided along one edge by a hook *f'*, project- ing upwardly from a plate *f*, which is secured above plate *a* to the lower face of plate *b* by means of the lugs *f*². The work thus finally reaches the needle *D* in a proper rectilinear 100 position and will be maintained in such position as it is drawn along by the feed-dog *g*.

In order to sew a ribbon to the upper and

- lower face of the work I employ two reels h i , of which one is placed above the plate b and the other below the table A. The reel h , Fig. 3, is hung upon a shaft h' between a pair of heads h^2 , to which it is clamped by a spring h^3 and nut h^4 . The shaft h' is connected to a standard h^5 , terminating at its lower end in a claw h^6 , that engages a rail h^7 . The upright h^5 is adjustable laterally upon the rail and 10 may be clamped in any desired position by a screw h^8 . The rail h^7 is secured to the plate b above the work B by means of the screws h^9 , surrounded by sleeves h^{10} , upon which the rail rests. Through an inclined perforation 15 h^{11} of upright h^5 passes an inclined arm h^{12} , which may be clamped in position by screw h^{13} . The upper ribbon E passes from the reel h through a forked guide h^{14} , which is adjustably secured to upright h^5 by screw h^{15} . 20 Thence the ribbon E passes through a similar guide h^{16} , Fig. 2, secured to the free end of arm h^{12} by set-screw h^{17} , and is finally exposed to the action of the needle.
- The lower reel i is secured to the table A 25 by hanger i' . From the reel i the lower ribbon F passes through a slot A' of table A and through a slot f^3 of plate f , Fig. 10, to the upper face of plate a and under an arm f^7 of plate f , to be finally sewed down by the needle.
- 30 The plate f is provided at its end with teeth f^4 , that are engaged by the spring-finger f^5 of a gage f^6 . This gage embraces the plate f and forms a stop, against which one edge of the ribbon E is guided. By setting the gage 35 farther in or out the machine is adjusted to different widths of ribbons.
- It will be seen that by my invention not only the fabric B but also the ribbons E E are so guided that they will always be fed under the 40 needle with a proper rectilinear motion. Thus, when the machine is driven by a motor, it is entirely automatic and needs only a gen-

eral supervision, which enables a single operator to tend a large number of machines.

What I claim is—

45 1. A guide attachment for sewing machines consisting of a guide plate, a vertically yielding tension bar, a rail, extending across the guide plate at a distance above the same, gages adjustable on said rail, a cloth feeding device, 50 and a stitch forming mechanism, substantially as specified.

2. The combination of a slotted guide plate with a guide rail and a pair of adjustable gages having depending lugs d^6 , that engage 55 the slot in the guide plate, substantially as specified.

3. The combination of a guide plate with a rail h' , a standard h^5 , adjustable thereon, a 60 reel-supporting shaft secured to the standard, a forwardly projecting arm h^{12} , and a pair of ribbon guides secured to the standard and the arm respectively, substantially as specified.

4. The combination of a main guide plate with a stitch forming mechanism, a lower reel, 65 a slotted guide plate f , having teeth, and located between the main guide plate and the stitch forming mechanism and a gage f^6 , having a finger that is adapted to engage said teeth, substantially as specified. 70

5. A guide attachment for sewing machines composed of a main guide plate, a tension bar, a guide bar, gages adjustable thereon, an upper and lower ribbon support, and an upper and lower ribbon guide, substantially as specified. 75

Signed at New York, in the county of New York and State of New York, this 23d day of November, A. D. 1894.
